UNITED STATES PATENT OFFICE

111,210

DESIGN FOR A COLOR INDICATOR NECKTIE RACK

James C. McCurrach, Brooklyn, N. Y.

Application July 8, 1938, Serial No. 78,347

Term of patent 7 years

To all whom it may concern:

Be it known that I, James C. McCurrach, a citizen of the United States and resident of New York city (Borough of Brooklyn), in the county of Kings and State of New York, have invented a new, original, and ornamental Design for a Color Indicator Necktie Rack, of which the following is a specification, reference being had to the accompanying drawing, forming a part thereof, and in which

Figure 1 is a perspective view of a color indicator necktie rack showing my new design; Fig. 2

is a view thereof in front elevation, and Fig. 3 is a view thereof in end elevation.

The front and back of the design are alike.

The horizontal, oblique and dotted lining indicate respectively the colors, blue, brown and gray.

I claim:

The ornamental design for a color indicator necktie rack, substantially as shown and described.

JAMES C. McCURRACH.
